SHOE-SIZE-TESTING DEVICE

Application filed May 16, 1929. Serial No. 363,515.

This invention relates to the art of shoe-making and is intended to provide a size testing device for shoes by which the fitness of a completed shoe to a foot of standard selected size dimensions may be determined in order to ascertain the correctness of the size indicia marked, or to be marked on such shoe.

Last makers are not only frequently changing the style and the size measurement 10 of shoe lasts, but also arbitrarily changing the size markings or indicia which are to be used on the shoes made on the respective lasts. As a consequence of these variations in practice, the size marks stamped on shoes afford 15 either confusing or unreliable data as to the actual size of the human foot which they will fit.

Heretofore in this art there has been no means of accurately or correctly determining, or ascertaining, what particular foot 20 having standardized measurements will be fitted by any given pair of shoes, since in no case does the last, upon which a particular shoe is made, conform exactly to a human 25 foot having the measurements for which that shoe was intended. Not only are there variations in styles, such for example as broad toe and narrow or pointed toe, but also in respect to the height of heels which affects 30 the posture or contour of the human foot, but there is the universal and necessary practice of adding certain so-called extensions or additional length sizes to the last in order that the toes of the foot of the wearer may not 35 strike against the tip or toe end of the shoe. In other words, every shoe must be longer than the foot that is intended to wear it.

It is possible by measuring a large number 40 of feet to reach an average of standardization in the ratios of ball width or ball girth to different overall lengths of the foot to arrive at practical standards of measurement sufficiently reliable to comfortably fit all feet 45 that are not markedly abnormal in respect to dimensions and contour.

The present invention provides a means for determining or ascertaining just what 50 standardized foot sizes should be assigned to any particular shoes that are being tested or examined. The invention, in general, com-

prises a sectional last, whose measurements correspond to those of the selected or standardized foot, which is divided on its medial longitudinal axis into side members with opposed flat interior bearing faces on their inner side and a medial or spacing member of predetermined thickness which acts according to its width to give additional increments of width and girth measurement. The medial spacing member, whose contour 55 lines either follow or lie within the contour lines of the inside faces of the side members, may be adjusted forwardly to determine the length size extension provided in the shoe that is being fitted. For convenience a length 60 size scale is associated with this medial plate to serve as an indicator or index of the actual length size extension in the toe portion of the shoe being tested. These and other features of the invention will be particularly described in the following specification and will be defined in the claims hereto annexed. 65

In the accompanying drawings I have illustrated a simple and convenient embodiment of the principles of the invention, in 70 which

Fig. 1 is a plan view of a testing device showing the spacing member advanced to the forward end of the shoe to ascertain the degree of extension that is provided for the 75 foot that the shoe will fit.

Fig. 2 is a side elevation of the device showing the spacing member in normal spacing position while indicating in dotted lines the advanced position for measuring the extension provided in the shoe being tested.

Fig. 3 is a modified form of spacing member in which the forepart and the rear part are hingedly connected together to allow relative changes of position when used in 80 testing shoes having low heels and shoes having very high heels.

In the practice of the invention, as illustrated in the drawings, a sectional last comprising an inside member 1 and an outside 85 member 2, whose flat opposed faces are adapted to match together to form a complete last having the dimensions of an assumed standard size of foot, which of course will be smaller in some respects than the last over 90

which the shoe intended for that foot was made.

The inside lateral member 1 comprises a rear or body portion 1^a extended from heel to ball and a forepart 1^b hingedly connected by a pivotal pin or bolt *c* to allow the angular relation of the rear and forepart to be changed in order to properly fit the last into a high heel or a low heel shoe by allowing it to assume the posture of the human foot when inserted in either type of shoe.

In a similar manner the outside lateral member 2 comprises a rear portion 2^a and a forepart 2^b hinged together by the pivot pin or bolt *d*.

It will be observed that the pivotal axis *c* on the inside member is some distance forward or in advance of the position of the pivotal axis *d*, the reason for this longitudinal offset setting of the axis of the two members being that the outside ball point of the human foot is some distance to the rear of the ball point on the inside of the human foot.

The two lateral members are adapted to be placed face to face to provide a form that shall have the narrowest width or ball girth measurement of a foot of given length, while means are provided for increasing the girth and width measurement in correspondence with the standard increase in width and girth measurements for greater width of foot of the same length. The means by which the last may be varied in width and girth to realize any predetermined width comprises, in this case, a spacing member or flat plate 3, whose contour lines, as indicated in Fig. 2 in part by dotted lines, either follow or lie somewhat within the contour lines of the adjacent faces of the lateral members for a reason presently to be described.

If a series of plates of different thickness, corresponding to the increase in standardized width sizes in the shoemaking art, is provided, it is possible by substituting different thicknesses of spacing or filling members to use the same lateral members for all width measurements of feet of any particular length. If the usual width size practice is followed these medial plates will vary in thickness from one another by one-twelfth of an inch in a consecutive series.

If the shoe being tested properly fits the last without the medial plate then the tester will know the width size of that shoe and, if the last, thus inserted, is permitted no longitudinal play in the shoe he will know from the standardized marking on his testing last the size of foot which that particular shoe is fitted to take. Should there be longitudinal or lateral play, or looseness, he may then insert the next larger size of testing last and may also insert different widths of spacing members until the shoe is properly fitted by the inserted device.

It is important, however, to determine the

degree of extension of length contained in the shoe beyond the length of the normal size foot. For this reason the spacing plate 3 is cut away over the instep and toe so as to lie somewhat within the upwardly sloping contour line of the side members, as indicated in Fig. 2, so that the spacing member may be forwardly adjusted, as indicated in Fig. 1, until the tip end of the plate abuts against the toe end of the shoe upper. To facilitate this forward adjustment of the spacing plate its rear end is provided with an upwardly extending ear or lug 3^a which can be readily seized by the fingers to advance and retract the plate.

In order to definitely indicate the amount of extension in shoe length sizes, I provide an indicating scale on the flat upper portion of one of the lateral members, the zero point of said scale being adapted to register with a cross mark 4 on the upper face of the spacing plate when the spacing plate lies in flush relationship with the toe portion of the lateral members. In Fig. 1, the spacing member is shown in position to indicate 1 1/2 length sizes.

As the posture of the human foot varies considerably when placed in a high heel shoe in contrast with its posture when in a low heel shoe, it would be necessary to have a separate series of plates for use with the hinged lateral members of the last when testing the two types of shoes where the spacing members are made as single or integral plates.

By providing a pivotal or hinge joint between the forepart and the rear part of the spacing member, the same spacing member may be used when testing both styles of shoes.

In Fig. 3, I have shown a spacing plate embodying this adjustable principle embracing the rear part 5 with the manipulating lug 7 and a forepart 6, which has a circular extension 6^a adapted to pivotally interlock with a circular recess in the forward end of the rear part 5 to afford a flat hinge joint for pivotally connecting the two members together without increasing the width or thickness of the plate at the hinge joint.

It will be understood that the term "last" as applied to this device is used to indicate any construction of foot form that can be fitted into a shoe to determine the length and width measurements thereof and is not limited to a shoe maker's last on which the shoe is built in the course of its manufacture.

What I claim is:

1. A shoe size-testing device embracing a sectional last having the dimensions and contour of a human foot of standardized size measurements, and divided along its medial longitudinal axis into complementary lateral members, and a flat medial spacing plate of a thickness to add a predetermined increment of width and girth measurement to the last

when correctly positioned between the lateral members, said medial plate being insertable between said lateral members when they are properly positioned inside the shoe, thereby adapting a last of given length size to fit into a shoe being tested.

5 2. A shoe size-testing device embracing a sectional last having the dimensions and contour of a human foot of standardized size measurements, a sectional last divided along its medial longitudinal axis into inside and outside members corresponding to the contour of the opposite sides of a selected foot, a medial spacing member of predetermined thickness whose contour lines follow and fall within the lines of the adjacent planes of the side member to permit forward adjustment of the spacing member when the members are assembled within the shoe and thereby indicate the length extension of the toe of the shoe beyond the remainder of the last.

10 3. A device for size-testing shoes embracing a sectional last having the standard size measurements and contour of a selected human foot divided on its longitudinal axis into separate lateral members, and a spacing member of known thickness interposed between said lateral members and longitudinally adjustable in relation thereto when 15 the three members are fitted into a shoe being tested, the spacing member and one lateral member being provided with length size indications to measurement in length sizes the extent of forward adjustment permitted the 20 spacing member.

25 4. A device for size-testing shoes embracing a sectional last having the standard size measurements and contour of a selected human foot divided on its longitudinal axis into separate lateral members, and a flat spacing member of known thickness adapted 30 for insertion between the lateral members to give the sectional last a predetermined and known foot size width measurement, each 35 lateral member comprising a rear part and a fore part pivotally connected to allow flexing them to correspond with different positions of a foot when inserted in shoes having different heights of heel.

40 50 5. A sectional last corresponding in contour and size measurements to the standardized dimensions of a selected foot comprising three longitudinal sections, the medial section comprising a thin flat spacing member 45 of known thickness, each of said members comprising a rear part and fore part hinged together on different transverse axes.

55 In witness whereof, I have subscribed the above specification.
